SAFETY BELT BUCKLE

George H. Jantzen, New York, N.Y., assignor to M. Steinthal & Co. Incorporated, New York, N.Y., a corporation of New York

Filed Mar. 7, 1967, Ser. No. 6,097

Term of patent 14 years

(Cl. D2—408)

FIG. 1

FIG. 2

FIG. 3

FIG. 4

FIG. 5

FIGURE 1 is a perspective view of a safety belt buckle showing my new design;

FIGURE 2 is a perspective view of the safety belt buckle;

FIGURE 3 is a side elevation view of the safety belt buckle as shown in FIGURE 2, the opposite side having substantially the same appearance;

FIGURE 4 is an end elevation view of the safety belt buckle opposite to the end shown in FIGURE 1;

FIGURE 5 is a bottom view of the safety belt buckle as shown in FIGURE 2.

The part with which the safety belt buckle locks is shown in broken lines for illustrative purposes only.

I claim:

The ornamental design for a safety belt buckle, substantially as shown and described.
